UNITED STATES PATENT OFFICE.

FRANK A. MERRICK AND EMMETT W. STULL, OF JOHNSTOWN, PENNSYLVANIA, ASSIGNORS, BY MESNE ASSIGNMENTS, TO WESTINGHOUSE ELECTRIC AND MANUFACTURING COMPANY, OF PITTSBURG, PENNSYLVANIA, A CORPORATION OF PENNSYLVANIA.

CONTROLLER FOR ELECTRIC MOTORS.

SPECIFICATION forming part of Letters Patent No. 708,158, dated September 2, 1902.

Application filed January 2, 1902. Serial No. 88,092. (No model.)

To all whom it may concern:

Be it known that we, FRANK A. MERRICK and EMMETT W. STULL, of Johnstown, in the county of Cambria and State of Pennsylvania, have invented a new and useful Improvement 5 in Controllers for Electric Motors, (Case B,) of which the following is a full, clear, and exact description, reference being had to the accompanying drawings, which form a part 10 of this specification.

This invention has relation to controllers for electric motors, and is more particularly designed to provide electromagnetic means of improved character for extinguishing or 15 "blowing out" arcs at the controller contacts. Considerable difficulty exists in providing in the limited space available in a controller-casing and in view of the difficulty of preventing magnetic leakage a blow-out magnetic 20 circuit which shall be sufficiently effective throughout the length of the controller-drum unless the strength of the magnet be made very much greater than would otherwise be necessary for the work to 25 be performed.

The present invention is designed to reduce largely the loss in efficiency due to magnetic leakage and also to provide for a more uniform distribution of the magnetic circuit 30 throughout the full contact length of the drum.

In accordance with the invention we arrange the blow-out coil adjacent to the central portion of the drum and secure to the 35 core of the said coil a vertically-extended pole-piece, whose end portions are made to carry the bearings for the drum, thus providing a magnetic circuit from the coil directly into the drum at both its ends. Furthermore, the 40 body of the drum itself being of magnetic material there is more or less magnetic flux across the air-space between the pole-piece and drum throughout the entire contact length of the latter. The return-circuit is 45 made through the casing of the controller, and said casing is so constructed as to direct the flux from the drum to the casing through the points where arcs tend to estab-

lish themselves, the direction of the lines of force being substantially perpendicular to 50 the direction of maintenance of the arc and therefore, as is well known, most effective in extinguishing action.

Our invention also consists in the novel construction, combination, and arrangement 55 of parts, all as hereinafter described, and pointed out in the appended claims, reference being had to the accompanying drawings, in which—

Figure 1 is a front view of a controller embodying the invention with a portion of the 60 casing removed, and Fig. 2 a section on the line 2-2 of Fig. 1.

In the figures, the letter A designates the 65 casing of the controller; B, the contact-carrying control-drum carried by a shaft; b, the contacts on said drum; C C', contact-fingers, and D the drums of a reversing and cut-out switch. This last-named switch does not enter into the present invention and is shown 70 only for completeness. Its drum being preferably of wood does not affect the magnetic circuit hereinafter described.

E designates the blow-out coil, which may 75 be connected in circuit in any usual or desirable manner. This coil is placed behind the drum B and is wound about a core F, which may form an integral projection from the rear portion of the casing A, as shown in Fig. 2. It is extended through the coil to a position 80 opposite one side of the drum, and firmly bolted or otherwise rigidly secured thereto is a pole-piece G. This pole-piece preferably consists of a flat bar of magnetic material presenting a flat side toward the drum. Its lower 85 end portion is bent in under the drum and seats the lower bearing g for its shaft. The upper bearing g', of magnetic material, is also carried by said pole-piece, which is steadied by being secured to the top A' of the casing 90 by a bolt g² or other suitable means. Behind the contact-fingers C' the door portion of the casing is formed with a vertical reinforcement H, of magnetic material, which serves to direct and concentrate the lines of 95 force through the arcing-spaces of the drum

at substantially right angles, the return-circuit being from the piece H around through the casing to the pole-piece. By making the pole-piece G carry the shaft-bearings leakage through such bearings is prevented. The top of the casing is formed of brass or other non-magnetic material, and consequently there is no magnetic leakage through it from the upper end of the pole-piece.

10 It is obvious that various mechanical changes may be made in the construction and arrangement of the various parts without affecting the invention. Hence we do not wish to limit ourselves to the precise construction 15 and arrangement herein shown and described.

Having thus described our invention, what we claim as new, and desire to secure by Letters Patent, is—

1. In a controller for electric motors, the 20 combination with a casing formed in part of magnetic material, and a controller-drum whose body and shaft are also of magnetic material, of a blow-out coil, a core supporting said coil, and a pole-piece carried by said 25 core and carrying the bearings for the said shaft.

2. In a controller for electric motors, the 30 combination with a contact-carrying drum having a body of magnetic material, of a blow-out coil adjacent to the central portion of said drum, a pole-piece carried by the said core, and carrying the bearings for the shaft of said drum, and a casing arranged to com-

plete the magnetic circuit through the said drum.

3. In a controller for electric motors, a blow-out coil adjacent to a contact-carrying drum of the controller, a pole-piece carried by the core of said coil, and bearings for the shaft of said drum carried by the said pole-piece. 40

4. In a controller for electric motors, the 45 combination of a casing having its body portion formed of magnetic material, a contact-carrying drum having its body and shaft of magnetic material, a blow-out coil adjacent to the central portion of said drum, a core for said coil carried by the said casing, a pole-piece for said coil carried by the casing and itself carrying the bearings for the said shaft.

5. In a controller for electric motors, the 50 combination with a contact-carrying drum having its shaft and body portion composed of magnetic material, a blow-out coil, and a pole-piece secured to the core of said coil and extending in opposite directions therefrom 55 parallel with and adjacent to the said drum, and bearings for the drum-shaft carried by the said pole-piece.

In testimony whereof we have affixed our signatures in presence of two witnesses.

FRANK A. MERRICK.
EMMETT W. STULL.
